I. Strauss

UNITED STATES PATENT OFFICE

103,475

DESIGN FOR A CURTAIN FABRIC

Ira Strauss, New York, N. Y.

Application February 4, 1937, Serial No. 67,443

Term of patent 3½ years

To all whom it may concern:

Be it known that I, Ira Strauss, a citizen of the United States of America, residing in Manhattan, county and State of New York, have invented a new, original, and ornamental Design for a Curtain Fabric, of which the following is a specification, reference being had to the accompanying drawing, forming part thereof, wherein,

The figure is a plan view of a piece of curtain fabric showing my new design.

I claim:

The ornamental design for a curtain fabric, substantially as shown.

IR A STRAUSS.
